UNITED STATES PATENT OFFICE.

DAVID FREEDLINE, OF BROOKLYN, NEW YORK.

HAT STRETCHER AND SHAPER.

1,380,201.

Specification of Letters Patent. Patented May 31, 1921.

Application filed March 17, 1920. Serial No. 366,562.

To all whom it may concern:

Be it known that I, DAVID FREEDLINE, a citizen of the United States, and a resident of the city of New York, borough of Brooklyn, in the county of Kings and State of New York, have invented a new and improved Hat Stretcher and Shaper, of which the following is a full, clear, and exact description.

10 The object of the invention is to provide a new and improved hat stretcher and shaper more especially designed for use in retail stores and arranged to permit the salesman to readily stretch and shape a hat to accurately fit the customer's head.

15 Another object is to permit of readily shaping any particular part of the hat along the base of the crown to accommodate bumps or other protuberances or irregularities on the customer's head.

20 Another object is to allow quick and convenient adjustment of the movable parts of the stretcher and shaper and to hold the same locked in the adjusted position.

25 Another object is to permit of readily ironing or steaming the rim or base portion of the crown of the hat.

With these and other objects in view, the invention consists of certain novel features 30 of construction as hereinafter shown and described and then specifically pointed out in the claims.

35 A practical embodiment of the invention is represented in the accompanying drawings forming a part of this specification, in which similar characters of reference indicate corresponding parts in all the views.

Figure 1 is a plan view of the improved hat stretcher and shaper;

40 Fig. 2 is an enlarged sectional side elevation of a portion of the same on the line 2—2 of Fig. 1;

Fig. 3 is a similar view of another portion of the same on the line 3—3 of Fig. 1; and

45 Fig. 4 is a sectional side elevation of one of the main stretching and shaping members with an auxiliary stretching and shaping member moved into active position on the said main stretching and shaping member;

50 Fig. 5 is an enlarged side elevation of a portion of the hat stretcher and shaper and showing more particularly the locking devices for the screw rods, one of the locking devices being shown in unlocking position and another in locking position;

Fig. 6 is a plan view of the improved hat

stretcher and shaper with the special continuous shaping band in position on the main stretching and shaping members; and

Fig. 7 is an enlarged sectional side elevation of the same on the line 7—7 of Fig. 6.

The base 10 of the hat stretcher and shaper is preferably made oval and formed with a number of recesses 11, preferably disposed radially on the top of the base 10, and in each of the said recesses 11 extends a nut 12 depending from a main stretching and shaping member 13 of segmental shape and mounted to slide inward or outward on the top of the base 10. The hat stretching 70 and shaping members 13 when in innermost position have their ends in close proximity and the said stretching and shaping members in the aggregate form an oval adapted to fit against the inner face of the lower 75 portion of the crown of a hat to be stretched.

In each of the nuts 12 screws a screw rod 15 abutting with its inner end on an abutment socket 16 forming part of the inner wall of the corresponding recess 11. The 80 screw rod 15 extends through the recess and through a supporting plate 17 fastened to the edge of the base 10, as plainly shown in Fig. 2. The outer end of each screw rod 15 terminates in a handle 20 projecting a 85 distance from the edge of the base 10 to allow the salesman to readily turn the screw rod with a view to move the nut 12 and the corresponding stretching and shaping member 13 inward or outward on the base 10 90 according to the direction in which the screw rod 15 is turned at the time.

A covering plate 25 closes the top of each recess 11 and this covering plate 25 is flush with the top of the base 10, and the covering plate is provided with an opening 26 through which extends the nut 12 and hence the covering plate 25 moves inward or outward with the nut 12 and the corresponding stretching and shaping member 13. By the 100 arrangement described the surface for the rim of the hat to rest on is continuous to permit of pressing or ironing the rim whenever it is desired to do so. To the under side of each covering plate 25 is secured a slide 27 engaging at its sides guideways 28 formed on the top of a lining 29 fitted into the corresponding recess 11. By the arrangement described the covering plate 25 and its slide 27 engaging the guideway 28 serve to properly guide the corresponding nut 12 and its stretching and shaping member 13 in-

wardly and outwardly on turning the screw rod 15.

It will be noticed that when a hat is placed with its rim onto the upper face of the base 10 and the covering plates 25 with the stretching and shaping members 13 extending within the lower portion of the crown of the hat and the said stretching and shaping members 13 are individually moved 10 outward by correspondingly turning the screw rods 15, then the lower portion of the crown is stretched at any desired point to any desired extent by turning the corresponding screw rod 15 with a view to more 15 or less move the corresponding stretching and shaping member 13 in an outward direction, to give the desired shape to the hat to fit the customer's head.

Each of the screw rods 15 is adapted to 20 be locked in place after the corresponding stretching and shaping member is moved into the desired position, and for this purpose use is made of locking catches 35 mounted to swing on pivots 36 attached to 25 the sides of the base 10. Each catch 35 is provided at its free end with a sharp eccentric edge 37 adapted to engage a corresponding thread on the screw rod 15 to hold the latter against turning, as will be readily 30 understood by reference to Fig. 5.

Each of the stretching and shaping members 13 is provided with one or more auxiliary stretching and shaping members, each 35 in the form of a screw 40 extending radially and screwing in the corresponding main stretching and shaping member 13. Each 40 of the screws 40 is provided with a conical head 41 adapted to be normally seated in a counter-sink 42 formed in the outer face of the corresponding main stretching and shaping member 13. When it is desired to stretch 45 a particular portion of the lower part of the crown of the hat for accommodating a bump or other projection then the corresponding screw 40 is screwed outward so that the head 41 is located a distance from the outer face 50 of the corresponding main stretching and shaping member 13, as will be readily seen by reference to Fig. 4. It will be noticed that the portion of the crown in contact 55 with the projected head 41 of the screw 40 provides a special recess in the crown to accommodate a bump or other projection on the wearer's head.

55 When it is desired to elongate or stretch the crown in one direction only then use is made of a segmental stretching and shaping member 50 having a boss 51 at its middle adapted to be seated on the outer face of one 60 of the end stretching and shaping members 13, as plainly indicated in Fig. 1. On the top of the middle portion of this segmental stretching and shaping member 50 is fastened a clip 52 by the use of a screw or other 65 fastening means 53, and this clip 52 is made

of spring steel fitting over the top and inner face of the corresponding main stretching and shaping member 13 to hold the segmental auxiliary stretching and shaping member 50 in position on this particular 70 main stretching and shaping member 13 to move with the latter into stretching and shaping position (see Figs. 1 and 2).

When it is desired to stretch or shape the base portion of the crown of a hat then use 75 is made of an evener band 60, preferably made of sheet metal and fitting exteriorly around the several main stretching and shaping members 13, as plainly indicated in Fig. 6. The band 60 is provided at one end 80 with a loop 61 through which extends slidably the other end of the band, and this other end of the band is provided with a spring clip 62 adapted to engage one of the main stretching and shaping members 13 85 to hold the band in position while in use. This clip 62 is similar to the clip 52 and hence further description of the same is not deemed necessary. By reference to Fig. 6, it will be noticed that any one of the main stretching and shaping members 13 or any 90 one of the auxiliary stretching and shaping members 40 may be moved into an outermost position to act on the band 60 so that the latter makes a bridging connection between adjacent stretching and shaping members 13 or between the members 13 and 40 moved into outward position, as shown in 95 Fig. 6.

From the foregoing it will be seen that 100 by the arrangement described a salesman can readily adjust the various stretching and shaping members to correctly stretch a hat with a view to accurately fit the same on a wearer's head. It will also be noticed that any particular part of the lower crown portion of the hat may be stretched and shaped to accommodate a bump or other protuberance or irregularity on the customer's head.

The hat stretcher and shaper is simple in construction, very durable and not liable to get easily out of order.

Having thus described my invention, I 115 claim as new and desire to secure by Letters Patent:—

1. A hat stretcher and shaper, comprising a base, a series of stretching and shaping members mounted to slide radially on the said base toward and from a common center, each stretching and shaping member having a depending nut, and radial screw rods screwing in the said nuts and having their inner ends abutting against the base and having their outer ends projecting from the 125 side edge of the base.

2. A hat stretcher and shaper, comprising a base having radially disposed recesses, guideways in the said recesses, stretching and shaping members mounted to slide radially 130

- on the said guideways and having depending nuts extending into the recesses and radially disposed screw rods screwing in the nuts and having their inner ends abutting 5 against the inner walls of the said recesses, the outer ends of the said screw rods projecting beyond the edge of the base.
3. A hat stretcher and shaper, comprising a base having radially disposed recesses, 10 guideways held in the said recesses, stretching and shaping members rising from the top of the base and having depending nuts extending into the recesses, covering plates moving with the said stretching and shaping 15 members and sliding on the said guideways, the said covering plates covering the said recesses and being flush with the top of the base, and screw rods screwing in the said nuts and having their inner ends abutting 20 against the inner walls of the said recesses, the outer ends of the said screw rods having handles projecting beyond the edge of the base.
4. A hat stretcher and shaper, comprising 25 a base having radially shaped recesses, guideways in the said recesses, stretching and shaping members mounted to slide radially on the said guideways and having depending nuts extending into the recesses 30 and radially disposed screw rods screwing in the said nuts and having their inner ends abutting against the inner walls of the said recesses, the outer ends of the said screw rods projecting beyond the edge of the base, 35 and screws screwing in the said stretching and shaping members and having heads at their outer ends forming supplementary stretching and shaping members.
5. A hat stretcher and shaper, comprising 40 a base having radially disposed recesses, guideways in the said recesses, stretching and shaping members mounted to slide radially on the said guideways and having depending nuts extending into the recesses 45 and radially disposed screw rods screwing in the said nuts and having their inner ends
- abutting against the inner walls of the said recesses, the outer ends of the said screw rods projecting beyond the edge of the base, 50 and screws screwing in the said stretching and shaping members and having heads at their outer ends forming supplementary stretching and shaping members, the outer faces of the said stretching and shaping members having countersinks and the said 55 heads being adapted to fit the said countersinks to be flush with the outer faces of the stretching and shaping members.
6. A hat stretcher and shaper, comprising a base having radially disposed recesses, 60 guideways held in the said recesses, stretching and shaping members rising from the top of the base and having depending nuts extending into the recesses, covering plates moving with the said stretching and shaping 65 members and sliding on the said guideways, the said covering plates covering the said recesses and being flush with the top of the base, screw rods screwing in the said nuts and having their inner ends abutting 70 against the inner walls of the said recesses, the outer ends of the said screw rods having handles projecting beyond the edge of the base, and an auxiliary segmental stretching and shaping member fitting exteriorly 75 against the outer face of one of the said first-named stretching and shaping members and a clip on the said segmental auxiliary stretching and shaping member and adapted to fasten the latter to the corresponding 80 stretching and shaping member.
7. In a hat stretcher and shaper, a movable stretching and shaping member having a threaded aperture countersunk in the outer face of the said stretching and shaping member, and a screw screwing in the said threaded aperture and having a head adapted to be seated on the said countersunk outer end of the aperture to be flush with the outer face of the stretching and shaping member. 85 90

DAVID FREEDLINE.
